UNITED STATES PATENT OFFICE.

HENRY G. VOIGHT, OF NEW BRITAIN, CONNECTICUT, ASSIGNOR TO THE RUSSELL & ERWIN MANUFACTURING COMPANY, OF NEW BRITAIN, CONNECTICUT.

LIQUID DOOR-CHECK.

SPECIFICATION forming part of Letters Patent No. 703,681, dated July 1, 1902.

Application filed February 28, 1902. Serial No. 96,088. (No model.)

To all whom it may concern:

Be it known that I, HENRY G. VOIGHT, a citizen of the United States, residing at New Britain, in the county of Hartford and State of Connecticut, have invented certain new and useful Improvements in Liquid Door-Checks, of which the following is a specification.

My invention relates to improvements in liquid door-checks; and the objects of my invention are economy in construction and efficiency in operation, especially with reference to preventing leakage between the spring-chamber and the liquid-chamber.

In the accompanying drawings, Figure 1 is 15 a vertical section on the line $x-x$ of Figs. 2 and 3, partly in elevation, of my liquid door-check. Fig. 2 is a detached plan view of the case, broken away on one side and with the cap removed. Fig. 3 is a reverse plan view 20 of the diaphragm that divides the spring-chamber from the liquid-chamber. Fig. 4 is a plan view of the cam and its shaft. Fig. 5 is a vertical section of the said cam and lower end of its shaft on the line $y-y$ of Fig. 4. 25 Fig. 6 is a partial section of the diaphragm, Fig. 3, on the line z .

A designates the case, having at its upper end a spring-chamber 6 and at its lower end a liquid-chamber, which is subdivided into 30 the cam-chamber 7 and cylinder 8, the said three compartments being eccentrically arranged, whereby the rear wall of the case, on which the securing-bracket 9 is formed, has the various parts of its length more nearly 35 the same distance from the door, and the cam-shaft is eccentric to the cylinder, so as to press more nearly on the center of the piston.

The cam-shaft 10 is provided with a lever-arm 11, of any ordinary construction, for use 40 with proper connections to turn shaft in opening and closing the door. As shown, the said shaft goes through the sleeve 12, to which the inner end of the spring 13 is secured, then through the diaphragm 14, with its cam 15 in 45 the cam-chamber in position to engage and reciprocate the piston 16 in the cylinder 8. In general these parts may be of any ordinary construction, although one feature of my invention is particularly adapted for a 50 door-check case having its liquid and spring

chambers eccentrically arranged. I construct the diaphragm 14 with an upwardly-extended hub 17, counterbored for a part of its length to form a stuffing-box, into which I place several leather washers 18, then on top of them 55 a coiled or spiral spring 19, made of flat wire of a rectangular form in cross-section, as clearly shown in Fig. 1, and then a cap 20 screwed in. The underside of the diaphragm 14 is provided with a central hub, on which 60 I form a short cylindrical portion 21, with a shoulder 22 at its upper end. At the outer portion of the under side of the diaphragm 14 there are two annular seats 23 and 24, with a groove 25 between them, preferably of a semi-circular form, as indicated by broken lines in Fig. 1 and full lines in Fig. 6. The edge of the diaphragm is threaded, and it screws into a threaded portion of the case at the bottom of the spring-chamber, the shoulder or 70 seat against which to screw the diaphragm being formed by the junction of the spring-chamber with the liquid-chamber. By reference to Figs. 1 and 2 it will be seen that this seat or shoulder is quite narrow on 75 the rear or bracket side of the case. I therefore place upon the said seat an annular plate 31 of Fig. 1 of the same diameter as the lower face of the diaphragm at its annular seat 23 and of a width equal to the radial distance from the outer side of the seat 23 to the inside of the seat 24 on the under face of said diaphragm, so as to form an abutment for both of the said annular seats 23 and 24 and to also cover or close the annular 80 groove between the said seats. The upper face of the diaphragm is provided with two recesses 26 to receive a proper key or wrench for screwing the diaphragm home, and these recesses have corresponding reinforcements 90 27 on the under side of the diaphragm, as shown in Figs. 1 and 3. The diaphragm will be packed with lead paint, and if properly applied the said paint will all be retained in the recess and make a tight joint, without 95 any of the paint working down into the liquid-chamber.

The upper side of the hub of the cam 15 is provided with an annular groove 28, into which the short cylindrical portion 21 of the 100

diaphragm 14 fits, only the groove is made deeper than the said portion 21 is long, so that a chamber is formed within the cam-hub below the end of the said portion 21, as shown in Fig. 1. Two holes 29 extend from the bottom of this chamber or bottom of the groove 28 to the under side of the cam, as shown in Figs. 1, 4, and 5. The upper end of the hub 30 of the cam and the shoulder 22 of the diaphragm 14 form opposing abutments for resisting the upward endwise movement of the cam and cam-shaft.

The liquid I prefer to use is oil, and then the chamber within the cam is an oil-collecting chamber. Any oil that passes between the end of the hub 30 and shoulder 22 and works downwardly therefrom will be collected in the chamber or space at the bottom of the annular groove in the cam and then passes downwardly through the holes 29 to the under side thereof, and thus any oil working upwardly on the shaft through the stuffing-box is prevented. This construction is simple and inexpensive and by actual use has been proved efficient.

I claim as my invention—

1. In a liquid door-check, the combination of the case having the liquid-chamber and

the spring-chamber eccentrically arranged, with the diaphragm screwed into the lower end of the spring-chamber to divide it from the liquid-chamber, the said diaphragm having the two annular seats on its under face with a groove between, and the annular plate seated on the shoulder at the junction of the liquid and spring chambers between the said shoulder and the annular seats of the said diaphragm, substantially as described.

2. In a liquid door-check, the combination of the case having the liquid-chamber and spring-chamber, with a diaphragm dividing the said chambers, and the cam-shaft and cam, the confronting faces of the said cam and diaphragm being formed with the annular groove and cylindrical portion fitted thereto of less length than the depth of the said groove for forming a collecting-chamber, and with endwise-bearing abutments outside of the said cylindrical portion, the said cam being also perforated from the said collecting-chamber downwardly to its under side, substantially as described.

HENRY G. VOIGHT.
